United States Patent Office

Des. 185,433
Patented June 9, 1959

185,433

TOOTHBRUSH BOX OR SIMILAR ARTICLE

Lewis J. Halberstadt, Williamsburg, Mass., assignor to Pro-Phy-Lac-Tic Brush Company, Florence, Mass., a corporation of Delaware

Application November 26, 1957, Serial No. 48,675

Term of patent 14 years

(Cl. D58—12)

Fig. 1.

Fig. 2.

Fig. 3.

Fig. 4.

Fig. 1 is a top plan view of a toothbrush box or similar article, showing my new design;

Fig. 2 is a side elevational view thereof with the cover removed therefrom;

Fig. 3 is an end elevational view as seen from the left hand end of Fig. 1;

Fig. 4 is an end elevational view as seen from the right hand end of Fig. 1; and

Fig. 5 is a bottom perspective view thereof.

The side not shown is the same as the side shown.

I claim:

The ornamental design for toothbrush box or similar article, as shown and described.
